UNITED STATES PATENT OFFICE

CHARLES B. HUDSON, OF AKRON, AND HENRY C. BOSTWICK, OF KENMORE, OHIO, AS
SIGNORS TO THE AKRON STANDARD MOLD COMPANY, OF AKRON, OHIO, A CORPO-
RATION OF OHIO

VULCANIZER

Application filed November 5, 1927. Serial No. 231,247.

This invention relates to vulcanizers, such as used in the curing of tires, tubes or the like, and particularly to vulcanizers of the well-known "watch case" type in which there is provided a central stationary mold member which is flanked by two swinging mold members, means being provided to lock the movable members against the stationary member during the vulcanizing operation, all of said members being provided with steam chambers.

One object of the invention is to secure a better locking arrangement than heretofore obtained, combining a rotating locking and clamping ring with a centrally located cam locking device so that as the mold sections are locked about their outer peripheries by the rotating locking ring, they are also locked at the interior of the vulcanizer. Another object is to improve upon the means for heating the mold sections, eliminating the objectionable exterior piping heretofore used in this type of equipment. Other objects of the invention are to improve upon various automatic features of this type of vulcanizer, and to provide safety devices which will prevent accidental injury to the operator.

These and other objects and advantages will be accomplished by the improvements shown, described and claimed herein, it being understood that exact conformity with the details of the invention is not necessary but changes and modifications may be made in specific embodiments of the invention. It will also be understood that the invention, in certain aspects, is not limited to the vertical watch case vulcanizer, but may be incorporated in other types of vulcanizer.

In the drawings in which the preferred form of the invention is shown,

Figure 1 is a side elevation of a complete unit comprising all of the features of the invention;

Figure 2 is a horizontal section on the line 2—2 of Figure 1;

Figure 3 is an end or edge view of the apparatus;

Figure 4 is an enlarged view of a detail of the locking ring showing the mold sections in open condition;

Figure 5 is a similar view showing the locked position of the parts;

Figure 6 is a detail of the throttle valve in the ring operating line;

Figure 7 is a plan thereof; and 55

Figure 8 is a section on the line 8—8 of Figure 6.

The watch case vulcanizer comprises the usual standard or base plate 1, upon the upper surface of which is secured the central stationary mold member 2, which is internally chambered as at 3, for the circulation of steam, the sides of the chamber being closed by removable and replaceable plates 5 having molding cavities 6 formed therein. Each 65 of these plates constitutes one section or side of a molding cavity, molds being here shown as designed for the vulcanization of a pneumatic tire, although the shape of the cavity may be altered for the molding of tubes or 70 other articles. The tire is shown at 8, mounted upon the usual curing ring 9 and having an air bag or expandible core 10 therein. The molding cavities are enclosed by the swinging or movable mold members 12 which are 75 also chambered, being closed in by removable plates 13 similar to the plates 5. These movable mold members are carried upon brackets 15 which are secured to vertical pins or hinge pins 16, which are mounted for 80 rotation in arms or brackets 17 extending from the central or stationary member.

In order to introduce steam in the vulcanizer economically and without excessive piping, the steam is conducted from a stationary supply pipe 20, preferably located over head, provided with branches 23, each of which passes through a stuffing box 21 secured to the upper end of the hinge pin 16. A rigid 90 hollow arm 22 extends from the stuffing box to the uppermost point in the swinging member where the steam is admitted to the rear of the plate 13, the outer side of the plate being chambered at 24 for the purpose of 95 insulating the movable mold member. To admit steam to the central or stationary mold member the hinge pin is provided with a vertical passageway 25 which communicates at its lower end with a horizontal passage 26 100

in the bracket 17, and thence to the chamber 3.

Steam passes out of the movable mold members through the pipe 30, which is rigidly attached to the lower side of the movable member, in the same manner as the pipe 22 and communicates with a stuffing box 32 on the lower end of the hinge pin 16. The discharge passage from each movable mold member is connected by piping 33 to a chamber 34 where the condensate collects, being removed through the drain 35. The steam from the stationary mold member passes out through pipe 38 to the same condensate chamber.

By the design of the parts as illustrated and described, the multiplicity of piping heretofore found necessary is greatly reduced, thereby simplifying and lessening the cost of the equipment, and lessening the labor or installation and maintenance, the only steam piping required to be done in installing the device being the connections for the steam inlet and outlet.

As the movable mold sections are brought into contact with the stationary sections they are guided and accurately centered by means of lugs 40 projecting from the lower side of the swinging members and adapted to ride upon rigid arms or positioning members 41 projecting from the stationary members.

Each movable section is designed to be locked against the stationary section by means of a rotating locking and clamping ring 45 which is rotatably mounted upon a rib 46 formed in the stationary section, this ring having a plurality of equally spaced arms 47, the inner surfaces of which are provided with tapered wearing plates 48. These plates are adapted to be brought into registration with and to ride upon corresponding tapered wearing surfaces 49 in lugs 50 projecting from the swinging mold members. As the ring is rotated in one direction the mold will be locked about its outer periphery, and as it is rotated in the opposite direction until the lugs are out of registration, it will be unlocked. The clamping ring is provided with a single elongating cam or drawing lug 55 which is located at a point opposite the hinge of the mold, which is designed to engage a cam surface 56 on one of the lugs and effect a preliminary closing of the mold. This also serves to "rim" up the tires on the clamping rings, which for this purpose may be attached to the mold sections rather than connected together as shown in Figure 2. On the opening movement of the clamping ring the mold is cracked, to break the adhesion between the two mold sections and is then partially opened by a combined breaking and opening lug 58 in the locking ring adapted to engage a lug 50 on the movable sections. The complete opening of the movable sections is accomplished by means of a short gear sector 59

on the ring which engages a corresponding sector 60 in the hinge pin 16, at the termination of the rotation of the ring which moves the swinging section to its full open position. The locking ring is moved to effect the various movements by means of a piston 65, actuated by the cylinder 66 and attached at its upper end to an ear 67 in the locking ring.

In addition to the functions which have already been described, the locking ring serves as a means for clamping the mold sections together at the center or about the inner circumference thereof. This operation will now be described. At the center of the vulcanizer are located two oppositely positioned brackets or plates 70 at opposite ends of which are formed inwardly projecting fingers or lugs 71. Mounted at the center of each movable section is a bearing member 73 in which is mounted a rotating shaft 74, the inner end of each shaft having secured thereto a cross head 75, the arms 76 of which are adapted to pass between the brackets 70 and to be moved into registration therewith, being provided with replaceable wearing plates 78, the engaging surfaces of the arms and the brackets being tapered or wedge shaped to effect the requisite drawing action. The shafts 74 are held in position by adjustable collars 80 and are keyed at their outer ends to levers 82, each of which projects over the face of the movable mold section and extends to the outer periphery thereof, being held in place by a guide plate 85 secured to the face of the movable member, and by a nut 86 on its shaft, which affords a means of adjusting the cross head relative to the brackets. A stop pin 87 limits the movement of the lever 82 in the unlocked position.

At its outer end each lever is provided with a socket 88, the inner end of which is flared slightly and is adapted to be entered by a pin 90 secured to the clamping ring. As the movable mold section is closed by the gears 59 and 60 and by the drawing lug 55, the pin 90 entering the socket 88 and as the ring continues its closing movement to lock the outer periphery of the mold, by the wedging of the lugs 47 and 50 the ends of the cross head engage the ends of the brackets 70 and exert a powerful squeezing action at the center of the mold.

It will thus be seen that the rotating locking ring performs the following duties in its movements in opposite directions about the mold. Assuming the mold to be open, the gear segments 59 and 60 first bring the movable section to a partially closed position. The drawing lug 55 then brings the two sections in contact and the plurality of spaced lugs lock the mold together about its outer periphery while at the same time the central shaft and its cross head exerts a powerful locking pressure at the center of the mold,

thereby preventing any springing of the mold about the inner surface thereof. On the reverse movement the mold is unlocked on its inner and outer peripheries, cracked, and moved to its final full open position. In addition to the above functions, the locking ring serves also to reduce its own speed of rotation in the manner to be described.

It will be evident that considerable pressure is required to actuate the ring in the performance of its locking or clamping operation and its breaking operation, but that little pressure is required to move the ring beyond that point so that means are provided for throttling the fluid pressure which operates the piston 65. Fluid pressure is admitted to the upper and lower ends of the cylinders through pipes 95 controlled by a hand operated valve 96 which communicates with the exhaust 97. Fluid pressure is admitted to the valve through a pipe 98 which is pivoted coaxially with the pivot 99 of the cylinder. This pipe is supplied through a valve casing 100 mounted in the base of the machine. The fluid under pressure (air or water) passes through the center of the casing, in the path of which is arranged the rotating pin 102, having a portion cut away as shown, and held in position by a backing spring 103 at the base of the casing. The upper end of the pin is provided with a forked arm 105 adapted to be engaged by a pin 106 on the ring. As the ring moves the pin closes up the passageway to the cylinder, and the fluid pressure is lessened. In this manner, the rotation of the locking ring may be slowed up as the mold is unlocked, otherwise, the full pressure would move the ring too rapidly for safe operation. The by-pass 109 with valve 110 provides for regulation of the pressure admitted to the cylinder around the throttle valve and by the combination of these elements the exact rate of movement of the locking ring can be accurately controlled.

In order to prevent accidental operation of the closing mechanism by the lever 96, a swinging catch 112 is located in the path of pin 114 on the piston 65. To operate the apparatus it is necessary for the operator to move both levers 96 and 112 simultaneously.

The operation of the apparatus will have been understood from the foregoing description, and the details thereof can be readily understood by one skilled in this art, it being observed that having explained the principles of its operation the invention may be embodied in other specifically different devices than that shown.

60 What is claimed is:

1. A vulcanizer having a stationary section and a movable section, a rotating locking ring on the stationary section, a center clamping device on the movable section, and means including connections between the

locking ring and the center clamping device to operate the locking ring and the center clamping device in unison to exert pressure upon the opposite sections respectively, said connections being engaged when the vulcanizer is closed and disengaged when the vulcanizer is open. 70

2. A vulcanizer having relatively movable sections, a clamping ring on one section having lugs thereon adapted to engage lugs on one of the other sections, a rotatable center shaft through the vulcanizer carried by one section, clamping lugs on the center shaft adapted to engage clamping lugs on the other section, an operating lever for the shaft, and means to engage the lever and the clamping ring. 75

3. A vulcanizer having relatively movable sections, a clamping ring on one section having lugs thereon adapted to engage lugs on one of the other sections, a rotatable center shaft through the vulcanizer carried by one section, clamping lugs on the center shaft adapted to engage clamping lugs on the other section, and an operating lever for the shaft, the lever being disengaged from the ring when the vulcanizer is opened, but engaged therewith when it is closed. 80

4. A vulcanizer comprising a pair of relatively movable mold sections, a locking ring about the sections, a pressure cylinder to operate the ring, a piston rod connecting the cylinder and the ring, and a safety catch in the path of the piston rod. 85

5. A circular mold having relatively movable sections, bayonet means to clamp the sections together about the outer periphery of the mold and bayonet means to clamp the sections together at the center thereof, each of said bayonet means including movable members, means including elements associated with the respective sections for connecting the movable members of said bayonet means together when the mold is closed, said elements being separable as the mold is opened, and means for moving one of said bayonet members to the locking position whereby said connecting means simultaneously moves the other of said bayonet members to locking position to tightly clamp the mold sections together at their centers and peripheries. 100

6. In a mold of the type described, a stationary section, a clamping ring movable about the stationary section, a movable section having portions thereof to be engaged by the clamping ring, axial bayonet clamping means including a movable element, a lever fixed to the movable element of said bayonet means, said lever and said clamping ring, having interengaging means thereon adapted to disengage when the movable section is moved to open the mold and to re-engage upon closing of the mold, and means for moving the clamping ring to lock the outer 115

portions of the sections together whereby the axial bayonet means simultaneously clamp the center portions thereof together.

7. In a mold of the type described, a stationary section, a clamping ring movable about the stationary section, a movable section having portions thereof to be engaged by the clamping ring, axial bayonet clamping means including a movable element, a lever fixed to the movable element of said bayonet means, said lever having means thereon engaging when the mold is closed with said clamping ring and adapted to disengage therefrom when the mold is opened, and means for moving the clamping ring to lock the outer portions of the sections together whereby the axial bayonet means simultaneously clamp the center portions thereof together.
8. A vulcanizer having a stationary section and a movable section, bayonet means for clamping the outer peripheries of said sections together, bayonet means for clamping the inner peripheries of said sections together, each of said bayonet means including a movable element, means for locking the movable elements for said bayonet clamping means together when the mold sections are closed, said means including interengaging members separable when the vulcanizer is opened, and means for moving said locked bayonet elements to simultaneously clamp the inner and outer peripheries of said sections together.
9. A vulcanizer having a stationary section and a movable section, bayonet means for clamping the outer peripheries of said sections together, bayonet means for clamping the inner peripheries of said sections together, each of said bayonet means including a movable member, means for locking the movable elements of said bayonet clamping means together when the mold sections are closed, said means comprising a central shaft on the movable element of the inner bayonet means, a radial lever fixed to said shaft, a stud on the movable element of the outer bayonet means adapted to engage in a recess in said lever, said stud being removed from said recess by opening of the vulcanizer, and means for moving said locked bayonet elements to simultaneously clamp the inner and outer peripheries of said sections together.

10. A vulcanizer having a stationary section and a movable section, a rotating locking ring about the vulcanizer adapted to clamp the outside of said sections together, bayonet means to clamp the center of the sections together, fluid pressure means to lock the locking ring and the center bayonet means simultaneously, and additional means operated by the movement of said locking ring to control the fluid passed to the fluid pressure means.
